J. F. KEENAN.

LOWERING DEVICE REGULATOR FOR SEWER PIPE PRESSES.
APPLICATION FILED APR. 30, 1913.

1,100,079.

Patented June 16, 1914.

UNITED STATES PATENT OFFICE.

JOHN F. KEENAN, OF TAYLOR, WASHINGTON, ASSIGNOR TO DENNY-RENTON CLAY AND COAL CO., OF SEATTLE, WASHINGTON, A CORPORATION OF WASHINGTON.

LOWER-DEVICE REGULATOR FOR SEWER-PIPE PRESSES.

1,100,079.

Specification of Letters Patent. Patented June 16, 1914.

Application filed April 30, 1913. Serial No. 764,544.

To all whom it may concern:

Be it known that I, JOHN F. KEENAN, a citizen of the United States, residing at Taylor, in the county of King and State of Washington, have invented certain new and useful Improvements in Lowering-Device Regulators for Sewer-Pipe Presses, of which the following is a specification.

This invention relates to the manufacture 10 of sewer-pipe.

The object of the invention is the provision of improved devices which are employed in regulating the action of the "forming-board" when lowering a pipe 15 from the mold into position to be deposited upon a carriage for removal to the pipe turning works.

The invention is illustrated in the accompanying drawings, wherein—

20 Figure 1 is a view in vertical longitudinal section of my invention applied to pipe-lowering devices. Fig. 2 is a horizontal section through 2—2 of Fig. 1. Fig. 3 is a transverse section through 3—3 of Figs. 1 25 and 2.

Referring to the drawings, the numeral 5 designates a mold disposed at a distance above the floor 6 of a factory and 7 is a "forming-board", so called, which is secured 30 to the lower end of the mold when the pipe is being formed in the latter by means of lugs 35 provided on said board by hooks 8 depending from the mold. The forming-board is supported upon the upper end of a piston-rod 9 of a cylinder 10 which is operated by a fluid under pressure and controlled by suitable valves (not shown) for regulating the raising and lowering of the forming-board.

40 In the process of manufacturing pipe a portion of a length is protruded from the lower end of the mold upon the recedence of the forming-board while the plastic material within the mold is subjected to pressure. The pressure acting on the material is then removed and the forming-board is withdrawn from the pipe through the agency of the power cylinder 10 to allow of the insertion of a "socket-board" 11 into the 50 hub of the pipe. This being accomplished, the forming-board is raised by the power cylinder against the underside of the socket-board and upon pressure being again applied to the material the pipe containing the 55 socket-board is lowered for a distance

through the office of the cylinder. The joint downward movement of the forming board and pipe is then interrupted to enable the pipe to be cut to length, whereupon the pipe is lowered by correspondingly lowering 60 the forming-board until the socket-board has been lowered into position, whereat the forwardly protruding prongs, such as 12, of bars 13 provided on a carriage 14, are brought with the latter under the socket-board 11 at diametrically opposite sides of the forming-board. When thus presented the forming-board is further lowered to deposit the pipe-supporting socket-board upon the referred to carriage prongs. The aforesaid devices are or may be of usual or suitable construction.

According to the present invention, I provide means whereby the downward travel of the forming-board is arrested to first 75 maintain the socket-board in position to have the carriage prongs introduced therebelow and when this is accomplished to allow the forming-board to be further lowered independently of the socket-board and the 80 pipe which are then borne by the carriage-prongs. To such ends, I rigidly secure at a predetermined height on the piston-rod 9, the collar 15 of a cross-head. At each side are apertured blocks 16 which travel on 85 guide-bars 17, Fig. 3. The blocks 16, as shown in the view, are integrally connected with the collar 15 by arms 18.

19 represent companion or side members of a frame and are secured with each other 90 by interposed spacing-pieces 20 and bolts 21 and 22. The bolt 21 which extends through corresponding ends of said side members is pivotally supported in bracket 23 and serves therewith as a hinge support for the frame. 95 Said frame is disposed so that piston-rod 9 extends through the opening between said members, as best shown in Fig. 2, and whereby the members are adapted to be encountered by the crosshead arms 18 when 100 the same is lowered with the piston-rod 9. Under the free end of the frame I provide therefor a tiltable prop. Said prop consists of an arm 25 having axially aligned trunnions 26 and 27 extending from its ends and 105 journaled in bearing boxes 28. An arm 29 is rigidly connected to or formed with the trunnion 26 and is pivotally connected with an upright rod 30 having at its upper end a tread plate 31. A lever 32 fulcrumed at 33 110

has one of its ends operatively connected with the rod 30 while its other end carries a weight 34 which is capable of maintaining the prop in its uppermost position, as indicated by full lines in Fig. 1, and similarly supporting the tread-plate 31.

The prop-arm 25 and the arm 29 constitute, in effect, a bell-crank lever. Normally, the arm 25 is as above mentioned, held in its upright position to retain the frame in its elevated position to be engaged by the cross-head to arrest the piston-rod 9 in its downward travel when the socket-board 11 is lowered upon the forming-board into position to permit the carriage-prongs being brought under the socket-board. When this is accomplished, the operator presses down with his foot upon the tread-plate 31, resulting in the rod 30 pushing down the prop-arm 25, through the medium of arm 29, into the position in which it is indicated by broken lines A in Fig. 1. The frame is thus lowered into dotted line position B whereupon the piston-rod 9 is unsupported and descends to lower the forming-board 7 into the broken line position C in the view. By thus withdrawing the forming-board, the socket-board 11 and the superposed pipe P are deposited on the carriage-bars 13. The operator retains his foot on the tread-plate until the pipe is conveyed away upon the carriage. Upon releasing the tread-plate the weight 34 becomes operable subsequent to the raising of the piston-rod to effect the uptilting of the prop-arm 25 which, in turn, tilts the frame into position to arrest the piston-rod in the following downward movement of the same.

What I claim, is—

- 40 1. In devices of the character described, a piston-rod, power appliances for controlling the raising and lowering of the piston-rod, an element rigidly connected to said piston-rod, a frame, and tiltable prop devices adapted to engage said element for stopping the downward movement of the piston-rod and means for actuating said prop whereby a subsequent lowering of the piston rod may be effected.
- 45 2. The combination with a piston-rod adapted to raise and lower a forming-board of a pipe-molding machine, of means adapted to interrupt at a predetermined height

the downward movement of the piston-rod, means for automatically retaining the afore-said means in operative position, and devices under the control of the operator for rendering the second named means temporarily inoperative. 55

3. The combination with the hoisting and lowering devices of a forming-board for a pipe-molding machine, a frame, a prop for said frame, means for maintaining said prop in position to hold the frame in position to arrest said devices at a predetermined elevation, and foot-actuated devices acting in opposition to said means whereby said prop is rendered inoperative to retain the frame in position to stop said devices. 60 65

4. In devices of the class described, the combination with a pipe mold, a socket-board for a pipe, a carriage, a forming-board upon which the socket-board is supported when lowering a pipe thereupon from said mold, a power controlled piston-rod supporting the forming-board, positive means serving to arrest the downward movement of the piston-rod whereby the socket-board is stopped in position to be received upon said carriage, and devices under the control of the operator whereby the afore-said means are rendered temporarily inoperative to allow the socket-board to be deposited upon the carriage. 70 75 80

5. In devices of the character described, the combination with the socket-board, a carriage, a forming-board, a power-controlled piston rod for supporting said forming-board, and an element provided on said piston-rod, of devices whereby said element is automatically engaged to interrupt the downward movements of the piston-rod and said boards to hold the socket-board in position to be deposited upon said carriage, said devices being also adapted to be influenced by the operator to disengage the same from said element to allow the further lowering of the piston-rod to deposit the socket-board on the carriage. 85 90 95

Signed at Seattle Wash., this 18th day of April, 1913.

JOHN F. KEENAN.
